UNITED STATES PATENT OFFICE.

JOHN H. LA LONDE, OF JACKSONVILLE, FLORIDA.

GAUGE COCK.

Application filed October 29, 1923. Serial No. 671,613.

To all whom it may concern:

Be it known that I, JOHN H. LA LONDE, a citizen of the United States, residing at Jacksonville, in the county of Duval and State of Florida, have invented a new and useful Gauge Cock, of which the following is a specification.

This invention relates to gauge cocks for steam boilers, locomotive engines and the like.

The object of the invention is to provide a gauge cock free from joints throughout its body and equipped with a spring mounted to hold the valve seated and the packing in place.

Another object is to so construct a cock of this character that the valve pin may be removed at any time while pressure is in the boiler.

Another object is to construct such a cock with a self-seating valve which prevents cutting of the valve or its seat incident to the forcing of the valve against its seat such as occurs when screwed in and which also avoids wearing or stripping of the threads.

Another object is to so construct such a valve that it may readily be ground in case of leakage without removing any part.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed without departing from the spirit of the invention.

In the accompanying drawings:—

Figure 1 represents a longitudinal section of a gauge cock constructed in accordance with this invention.

Fig. 2 is a detail vertical section taken on the line 2—2 of Fig. 1.

Fig. 3 is a similar view taken on the line 3—3 of Fig. 1, and

Fig. 4 is a detail perspective view of the outer end of the valve stem or pin.

In the embodiment illustrated, the cock constituting this invention comprises a one piece body 1 free from joints throughout and having a reduced externally threaded extension 2 at its inner end for connection

with the boiler with which it is to be used. A bore 3 extends longitudinally through the center of the body 1 and merges at its outer end into a valve seat 5 to receive a cone-shaped valve 6. This valve 6 has a pin or stem 7 extending outwardly through a hollow chamber 1^a formed as an extension of the valve body 1. This stem 7 extends through a leak proof packing 8 and projects beyond the gauge body said projecting end being longitudinally slotted as shown at 9 for a purpose presently to be described. A coiled spring 10 surrounds the valve stem 7 and bears at one end against a shoulder 11 on the valve 6 and at its other end against 70 a collar bearing against the packing 8 and exerts its tension to normally hold the valve seated and the packing 8 in place.

An escape pipe 12 extends laterally from the chamber 1^a and is designed as an outlet 75 for the steam or water which enters said chamber when the valve 6 is unseated.

A cut-out cock 4 extends transversely of the body and intersects the bore 3 thereof in advance of the valve seat 5. This cut-out 80 cock 4 is of ordinary construction being tapered in form to insure its proper seating and it has a bore 4^a extending transversely therethrough and designed to register with the bore 3 when the cock 4 is open, 85 and when the cock is turned it cuts off communication between the bores 3 and 4^a and prevents the fluid from the boiler passing out to the chamber 1^a.

A split collar 13 is mounted on the chamber 1^a in a suitable groove provided for this purpose and is composed of two semi-circular sections 14 and 15 hingedly connected at one end as shown at 16 the other ends of said sections having outwardly extending 90 apertured ears 17 and 18 to receive a thumb screw 19 which connects an L-shaped lever 20 with said collar. The inner end of arm 21 of said lever is inturned laterally and positioned between the ears 17 and 18 and 95 connected by the thumb screw 19. The arm 21 normally extends parallel with the chamber 1^a and the lateral arm 22 on said lever is positioned in advance of said chamber and is designed to form a hand grip for use 100 in connection with a pivoted arm 23 carried by the arm 21 at a point spaced inwardly from arm 22 as shown clearly in Fig. 1. The pivoted arm 23 has an outwardly and laterally extending finger 24 at 110

its free end which is designed to form a stop to limit the outward swinging movement of the arm 23.

The slotted end of the valve stem 7 straddles the arm 23 and is detachably connected therewith in any suitable manner.

In the use of this gauge cock the parts being in the position shown in Fig. 1, when it is desired to unseat valve 6 to permit the 10 fluid in the boiler to pass out through the escape pipe 12 to disclose whether sufficient steam has been generated therein or for other purposes, all that is necessary is to grasp the pivoted arm 23 using the arm 22 15 in connection therewith and forcing said arm 23 toward arm 22 thereby moving the valve stem 7 outwardly against the tension of the spring 10 which operates to unseat the valve 6. Immediately upon the release 20 of the arm 23 the spring 10 will reseat the valve 6.

When for any reason it is desired to remove the valve or its stem the cut-out cock 25 4 is turned to close the bore 3 and by unscrewing the nut 25 said valve and its stem may be removed it being of course understood that the stem is first disconnected from the arm 23.

When it is desired to grind the valve 6 or 30 its seat 5 all that is necessary is to disconnect the stem 7 from the arm 23 and insert a suitable tool in the open slot 9 and rotate the valve on its seat in the usual manner for grinding it.

35 From the above description it will be ob-

vious that a valve constructed as herein shown and described will be self-seating under the tension of the spring 10 avoiding the rotating of the valve such as is necessary when a threaded connection is employed, 40 thus avoiding cutting of the valve or its seat and also wear and stripping of the threads.

Various changes in the form, shape, proportion and other minor details of construction may be made without departing from 45 the principle or sacrificing any of the advantages of the claimed invention.

I claim:—

A gauge cock comprising a hollow body provided with a spring seated valve for 50 closing one end, said valve having a stem extending through and slidably mounted in the other end, a split collar encircling said body intermediate its ends and held against longitudinal movement thereon, an L-shaped 55 member pivotally mounted at one end on said collar the other end of said member extending transversely across the path of said stem and spaced from the outer end of the stem, an arm pivoted to said member and connected with said stem and adapted to be moved toward the transversely arranged portion of the member to unseat the valve.

In testimony that I claim the foregoing as my own, I have hereto affixed my signature in the presence of two witnesses.

JOHN H. LA LONDE.
